UNITED STATES PATENT OFFICE.

CHARLES REMI ENGEL, OF YOMAN, WASHINGTON.

RIVETING MACHINERY.

1,383,915.

Specification of Letters Patent. Patented July 5, 1921.

Application filed September 15, 1919. Serial No. 323,841.

To all whom it may concern:

Be it known that I, CHARLES REMI ENGEL, a citizen of the United States, residing at Yoman, in the county of Pierce and State 5 of Washington, have invented certain Improvements in Riveting Machinery, of which the following is a specification.

My invention relates to machinery in which a reciprocating motion is required, 10 and in which the entire reciprocating parts can be forcibly lowered, without stopping the reciprocation, for such work as riveting, chiseling, mortising, etc., thereby causing a steady progression in the work being 15 cuted.

Such machinery, usually driven by belting connected with a line-shaft, must bear a certain relation to the line-shaft, because of the very limited ways in which belting can 20 be caused to transmit power.

My invention has for its object the elimination of these drawbacks, and to provide a machine that can be placed anywhere, regardless of the position of other machinery, 25 or line-shafting. This machine is to be driven by compressed air which can be led anywhere by means of a pipe.

With this object in view my invention consists in the construction and combination of 30 elements as hereinafter described.

Referring to the drawings: Figure 1 is a side elevation of the entire machine with a cross-section through a portion of the column showing the counter-weight, and with 35 a cross-section through the pneumatic hammer showing all the movements of the reciprocating parts, and a cross-section through a portion of the hammer supporting arm, showing the teeth of the pinion en- 40 gaged with the rack on the hammer barrel; Fig. 2 is a side elevation of the pinion, pull-down handle, and operating valve; Fig. 3 is an end elevation of Fig. 2, showing a cross-section on line *a—a* of Fig. 2; Fig. 4 is a cross-section of a foot valve to be used 45 in lieu of the valve in handle; Fig. 5 is a front elevation of the entire machine, showing the foot valve in dot and dash lines.

Referring in detail to the drawings. 1 is 50 the base with means provided for receiving and clamping the column 2, which is cylindrical and hollow, thereby providing a space for the counterweight 3. On top of the column is a cap 4 with means provided for receiving the pulleys 5 and 6; over these pulleys and through the cap, and into the

column, moves a chain or cable which is flexible and connected to 3 at one end and 7 at the other end. 8 is the hammer supporting arm which can be raised or lowered or 60 rotated on and around 2, this arm is also provided with means for clamping it fast to 2. The outer end of 8 is adapted to receive the barrel of the pneumatic hammer 9, this barrel has teeth 10, known as a rack cut on 65 a portion of its face; these teeth engage with similar teeth cut on pinion 11, which is rotated or oscillated by means of handle 12. The barrel 9 is suitably bored to accommodate the reciprocating piston or hammer 13; 70 in the lower end of the barrel is driven a tool-bushing 14, the lower end is also fitted with a tool-retaining, collar-housing 15. Number 16 is the collar and 17 the tool. The upper end of the barrel is adapted to 75 receive the barrel-head 18, and the air-distributing-head 19, and the pipe-fitting 7, to which is fastened a flexible tube 20. The other end of this tube is connected to nipple 21, which is fastened into valve-cage 22. 80 This valve-cage is adapted to receive handle 12, and nipple 23, on which is fastened another flexible tube 24, which is connected directly to the source of supply of the compressed air. 85

The inner end of handle 12 is shaped so as to form a seat for valve 25, whose stem runs through the entire length of handle 12, and on whose outer, extended end is fastened a push-button 26. In order to keep 90 this valve closed except when pressure is applied to 26, a compression spring 27, is provided, one end of which seats in a recess in the head of valve 25, and the other end seats in a deep recess in nipple 23. 35 is the body 95 of the foot valve suitably machined to accommodate valve 36 (on whose upper end is fastened a push button 37) and plug 38 which is recessed to act as a retainer for the compression spring 39 which keeps valve 100 closed except when pressure is applied to 37.

When foot valve is used in lieu of valve in handle the source of air is connected to opening 40 thence it passes through valve opening when pressure is applied to 37, to 105 outlet 41 to which is connected tube 20. The air now follows precisely the course as hereinafter described.

In operation, the handle 12 is grasped and lowered so as to bring tool down on the 110 work, then pressure is applied to 26 by means of the thumb; this action opens valve

25 and permits the compressed air which flows through the hollow nipple 23, to pass through the valve into the end of handle 12, thence through a hole bored at right angles to the axis of handle and connecting with the hollow nipple 21 into the tube 20; this tube conveys the air to 7 which is hollow and passes the air to 19 which distributes the air through holes 28 in 18 and then 10 through holes 29 bored in the barrel parallel to its axis and surrounding the piston chamber until it reaches the recess 30.

The air now exerts its pressure under the shoulder of the piston 13, and forces the 15 piston upward until the holes 31, in the lower end of piston come into alignment with the recess 30, of the barrel; the air now passes through these holes 31, into the chamber of the piston 32, and being checked 20 in its upward rush, because of the head 18, it now expands and forces the piston downward until it strikes the tool 17. The air which is now under reduced compression is exhausting through the same port holes 25 31, through which it entered the piston, into the long recess 33 of the cylinder and thence through an exhaust port 34, which connects recess with atmosphere. This completes the two cycles of motion and this action 30 will be repeated as long as the valve is kept open.

In the present embodiment of my invention the device is shown with a rivet-set in the tool-holding end of the hammer. It is, 35 however, understood that I do not wish to limit my device to riveting nor to restrict myself to the details of the construction shown, since various changes may be made by those skilled in the art without deviating 40 from the principle of my invention.

Having thus described my invention, what I claim and desire to secure by Letters Patent is:

1. A pneumatic machine comprising a 45 main supporting standard provided with a base, a hammer supporting arm adjustably supported by said standard, said arm being adapted to swing about the axis of said standard and being adjustable of position 50 along said axis, a pneumatic hammer supported by said hammer supporting arm, said hammer being provided with a rack engaging with a pinion supported by said arm, said pinion being provided with an operating 55 lever whereby said hammer may be raised or lowered, means integral with said operating lever for controlling the air sup-

ply to said hammer, said hammer being provided with means for holding tools adapted to pneumatic hammer work, said base acting as a support for the work to be executed, and means for counterbalancing the weight of said hammer and its attached elements. 60

2. A pneumatic machine of the class described comprising a main supporting member provided with a base and an extending arm, a pneumatic hammer adjustably supported by said arm and being provided with a rack, a pinion supported by said arm and engaging with said rack on said hammer, 65 said pinion being provided with an operating lever whereby said hammer may be raised or lowered by operating said lever, means integral with said lever for controlling the air supply to said hammer, said hammer being provided with means for holding tools adapted to pneumatic hammer work, said base acting as a support for the work to be executed, and means for counterbalancing the weight of said hammer and 70 its attached elements. 75

3. In a pneumatic machine of the class described, the combination of a pneumatic hammer, a supporting frame supporting said hammer and provided with a supporting table for work to be executed, means for raising and lowering said hammer in said frame, said means comprising a pinion supported by said frame and engaging with a rack on said hammer and a lever for operating said pinion, and means associated with the operating lever of said pinion for controlling the air supply to said hammer. 85 90

4. In a pneumatic machine of the class described in combination with a pneumatic hammer supported by a frame, a means for raising and lowering said hammer in said frame and means for controlling the air supply to said hammer, said means for raising and lowering said hammer comprising 100 a pinion provided with an operating lever, said pinion being supported by said frame and adapted to engage with a rack on said hammer, said means for controlling the supply to said hammer comprising a valve associated with said operating lever. 105

In testimony whereof, I have signed my name to this specification in the presence of two subscribing witnesses, this 5th day of Sept., 1919.

CHARLES REMI ENGEL.
